D34-2

SR

OR D 17,634

UNITED STATES PATENT OFFICE.

HENRY PODMORE, OF TRENTON, NEW JERSEY.

DESIGN FOR A SLOP-JAR.

SPECIFICATION forming part of Design No. 17,634, dated August 16, 1887.

Application filed February 2, 1887. Serial No. 226,335. Term of patent 7 years.

To all whom it may concern:

Be it known that I, HENRY PODMORE, a citizen of the United States, residing at Trenton, in the State of New Jersey, have invented and produced a new and original Design for Slop-Jars and other Analogous Vessels, of which the following is a description, reference being had to the accompanying photograph, forming part thereof.

10 The leading feature of my design consists in the main body of a slop-jar or other analogous vessel of a generally rounded or bulbous form, having those parts of the body from which the lower ends of the handles spring flattened, so as to present a circular or oval plane surrounding the base of each handle, one of which planes is shown at A in the photo-

tograph, the upper ends of the handles springing from shoulders above the said planes, and also having the top of the vessel scalloped.

20

What I claim is—

25 The design for a slop jar or other analogous vessel with its main body having a scalloped top and of a generally rounded or bulbous form, having the sides of the bulb flattened to present planes, from each of which springs the lower end of a handle, the upper ends of the handles springing from shoulders above said planes, as shown and described.

25

HENRY PODMORE.
